US00D896232S

(12) **United States Design Patent** (10) Patent No.: **US D896,232 S**
(45) Date of Patent: **** Sep. 15, 2020**

(54) **HOUSING MODULE FOR AN ELECTRONIC DEVICE**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Markus Diebel**, San Francisco, CA (US); **Aidan R. Gallagher**, San Francisco, CA (US); **Jason M. Gillier**, San Jose, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Derek C. Krass**, Santa Cruz, CA (US); **Sowmya Laxminarayanan**, San Jose, CA (US); **Jason B. Neevel**, Santa Clara, CA (US); **Peter Russell-Clarke**, San Francisco, CA (US); **Benjamin Andrew Shaffer**, San Jose, CA (US); **Jason P. Shannon**, Sunnyvale, CA (US); **Mikael Silvanto**, San Francisco, CA (US); **Sung-Ho Tan**, San Francisco, CA (US); **Clement Tissandier**, San Francisco, CA (US); **Eugene Antony Whang**, San Francisco, CA (US); **Rico Zörkendorfer**, Jackson, WY (US)

(73) Assignee: **Apple Inc.**, Cupertino, CA (US)

(**) Term: **15 Years**

(21) Appl. No.: **29/691,313**

(22) Filed: **May 15, 2019**

(51) **LOC (12) Cl. 14-02**

(52) **U.S. Cl. D14/439**

(57) **CLAIM**

The ornamental design for a housing module for an electronic device, as shown.

DESCRIPTION

FIG. 1 is a bottom front perspective view of a housing module for an electronic device showing the claimed design;

FIG. 2 is a top rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the housing module for an electronic device that form no part of the claimed design.

FIG. 1

FIG. 3

FIG. 4

FIG. 5

FIG. 6

FIG. 7

FIG. 8

UNITED STATES PATENT AND TRADEMARK OFFICE
CERTIFICATE OF CORRECTION

PATENT NO. : D896,232 S
APPLICATION NO. : 29/691313
DATED : September 15, 2020
INVENTOR(S) : Akana et al.
